ATTORNEY

UNITED STATES PATENT OFFICE.

ALFRED W. SOBE, OF NEW YORK, N. Y.

ADJUSTABLE ALIGNING GAUGE.

Application filed January 15, 1921. Serial No. 437,377.

To all whom it may concern:

Be it known that I, ALFRED W. SOBE, a citizen of France, residing at New York, in the county of New York and State of New York, have invented certain new and useful Improvements in Adjustable Aligning Gauges, of which the following is a specification.

The main object of this invention is the provision of an implement useful to guide plasterers, decorators, carpenters, and other interior workers or finishers in their work in laying out designs, jambs, moldings, etc.

Another object is to provide such a device of simple construction and operation, which is at the same time inexpensive in cost of manufacture and which may be quickly and securely set in any desired position for the running of a guide line, and which may readily be removed from any position.

The above and other objects will become apparent in the description below, in which similar characters of reference refer to like-named parts in the drawings, in which:—

Figure 1 is a fragmentary perspective view of the interior of a room illustrating one application of the device.

Fig. 2 is a plan view of the device.

Fig. 3 is an edgewise view of the same.

Fig. 4 is an enlarged perspective view of the slidable tongue to which a guide line may be secured.

Referring to the drawings, the numeral 1 represents one of the end members of the device and 2 the other, these members being joined by a flexible strip 3, and rivets or screws 4 secure the members 1 and 2 rigidly to the strip 3. Fixed in members 1 and 2 are outwardly inclined pointed pins 5 adapted to grip into wood or other material to hold the device in position, and finger pull rings 6 are pivotally attached to the ends of the strip by means of which the device may be held in one hand and bent as desired.

Near the outer edge of the member 2 is mounted a pair of spaced parallel guides 7 constituting a slideway 8 in which a plate 9 is slidably mounted, the plate having a flexible tongue 10 and a resilient clip 11 is cut out of the body thereof and adapted to press against the base of the runway in order to resiliently retain the slide plate in any position in the runway.

The tip of the plate is also adapted to press against the wall or surface by which

the member 2 is supported, and a guide wire or cord may be suspended from or secured to said tongue.

One of the guides 7 is provided with a 60 scale as shown.

In many lines of construction work as carpentering, plastering and decorating, it is often necessary to lay lines parallel to some definitely fixed point as a wall, ceiling 65 or floor, an accomplishment usually attained by driving nails in to the walls or floors, connecting them with a chalked cord which on being snapped imprints a mark on the adjacent surface. If other lines parallel to 70 the first are required other nails must be placed and later withdrawn causing damage or defacement to the surfaces in which they were driven.

These evident objections are very materially overcome by the use of the device, which may be attached to practically any surface without serious damage by means of its small stout spurs, the flexible metal strip permitting its application in corners, over 80 moldings and other places.

In wall decorations the device may be attached to wall and ceiling, a plumb line depending from the slide acting as a guide positioning material in perpendicular arrangement.

In floor laying it may be desirable to use two of these devices one at either side of the room and connecting the slides by a chalked line or wire, arranged parallel by 90 measuring from a wall, other parallel lines being obtained by moving the slides along the graduated plates.

Having thus described my invention what I claim as new and desire to secure by Letters Patent is:—

1. A device of the class described comprising an elongated resilient member, elongated head elements attached to each end of said member transversely thereof, the heads being provided with spurs for attachment to surfaces meeting at an angle.

2. A device of the class described comprising an elongated resilient member, elongated head elements attached transversely to each end of said member, means for detachably engaging the device to surfaces meeting at an angle, there being a T shaped slot arranged longitudinally on one of said heads, and a slide operable in said slot.

3. A device of the class described comprising an elongated resilient member, elon-

gated head elements attached transversely to each end of said member, means for detachably engaging the device to surfaces meeting at an angle, one of said heads having a 5 T shaped longitudinally extending guide slot, there being a graduated scale adjacent the slot, a slide operable in the slot and co-

operating with said scale, resilient means formed with said slide adapted to maintain it in adjustment, and grips for releasing the 10 device from the supporting surfaces.

In witness whereof I affix my signature.

ALFRED W. SOBE.
